"B" is a vertical swing valve to swing as the cars may run in either direction
so as to deflect the air towards the opening below." It
This differs from Figure 11,268 wherein the valve hangs vertically. The
"Valve B" swings like an ordinary door.

P and Q are tubes to moisten the air. Water from these tubes
impinges on discs G.

What I claim is a small door that may be opened
or shut in connection with and as part of a car
window that may be raised or opened in the
usual way.
